KNITTED FABRIC AND METHOD OF
MANUFACTURING THE SAME

Ester Hughes, New York, N. Y., assignor to
No-Run Corporation, Wilmington, Del., a cor-
poration of Delaware

Application February 8, 1941, Serial No. 378,008

5 Claims. (CL. 66—169)

This invention relates to knitted fabrics and methods of manufacturing the same. The invention refers more particularly to so-called non-run fabrics which must be so knitted that the breakage of the thread will not cause the formation of a run extending throughout the fabric.

An object of the present invention is the provision of a runproof knitted fabric which is particularly suitable for hosiery, and which is of light weight and texture.

Another object is the provision of a simple and inexpensive method of manufacturing runproof knitted fabrics which do not differ in any marked degree either in appearance or in elasticity and flexibility from plain knitted goods commonly employed in the manufacture of hosiery.

A further object is the provision of a knitted fabric of the anti-run type which can be made at high speed, either tubular or flat, and either by the hand needle method or by machinery.

Yet another object of the present invention is the provision of a non-run knitted fabric which has a novel and ornamental appearance and a relatively smooth outer surface, and which offers substantial resistance to the extension of a run resulting from the breakage of one of the loops constituting the fabric.

Other objects of the present invention will become apparent in the course of the following specification.

In accomplishing the objects of the present invention, it was found desirable to provide a knitted fabric having twisted or turned loops, so that the legs of such loops cross each other close to the bight of a loop of a preceding course. The twisted loops may constitute each alternate course of the fabric, or each course of the fabric may consist of such twisted loops.

I found that in the case of the rupture of the thread of a loop, the crossing legs of a loop in a preceding course and the same wale, co-operate with the adjacent thread portions to tie the ends of the ruptured loop as a pull is being exerted upon the fabric, with the result that an extension of the run is effectively prevented.

The invention will appear more clearly from the following detailed description when taken in connection with the accompanying drawings showing, by way of example, preferred embodiments of the inventive idea.

In the drawings:

Figure 1 is a diagrammatic enlarged front view of a fabric made in accordance with the principles of the present invention.

Figure 2 is a diagrammatic fragmentary front view on an enlarged scale, illustrating the manner in which a run is prevented after the rupture of a loop.

5 Figure 3 is a diagrammatic perspective view illustrating a method of producing the fabric shown in Figure 1 by hand knitting; and

Figure 4 is a diagrammatic front view illustrating another fabric made in accordance with the 10 principles of the present invention.

Figure 1 of the drawings illustrates diagrammatically a piece of knitted fabric 10 which may be knit by hand on the usual hand-knitting needles 11 and 12 (Fig. 3), or which may be 15 knitted upon circular or flat knitting machines, wherein the yarn is delivered to a series of needles which, in conjunction with other accessory devices, draw yarn into stitches to form course after course of knitted fabric.

20 As shown in Figure 1, the fabric includes wales 19 to 23, plain courses 13 to 15 and courses 16 to 18 consisting of twisted loops.

In tracing the formation of one of the twisted-loop courses, for instance the course 17, it is 25 apparent that the loop 24 which is situated in the wale 19, consists of a bight 25 and two legs 26 and 27. The bight 25 extends over the legs 28 and 29 of a loop 30 situated in the same wale 19, but in the following course 14 consisting of 30 loops of the usual type.

The legs 26 and 27 of the loop 24 cross each other closely to the bight 31 of a loop 32 situated in the preceding course 13, consisting of plain knitted loops. The left-hand leg 26 of the loop 35 24 (looking in the direction of Figure 1) extends over the leg 27 and under the bight 31 of the loop 32. Then the leg 26 continues in the form of a downwardly extending bight 37 extending over the right-hand leg 34 of the loop 32 and 40 the left-hand leg 35 of the loop 36 which are all situated in the preceding course 13.

The bight 37 is continued as the right-hand leg 38 of the loop 33 which is situated in the course 17 next to the loop 24. The leg 38 extends under the bight 39 of the loop 36 in the course 13 and also under the left-hand leg 40 of the loop 33 which crosses the leg 38; the leg 40 extends through the loop 36 to form the following downwardly extending bight 41 embracing adjacent legs of the loops 36 and 42 in the course 13. This arrangement is repeated throughout the course 17 and in similar courses 16, 18, etc.

The course 14 which follows the course 17, is the usual plain knitted course so that, for instance, its loop 30 has two legs 28 and 29 which

extend under the bight 25 of the loop 24 in a preceding course 17, while the bight 43 of the loop 30 extends over the crossing legs 44 and 45 of a loop 46 situated in the same wale 19 and in the subsequent course 18. Other loops of the course 14 and of similar courses 13, 15, etc., are arranged in the same manner.

It is thus apparent that the fabric 10 consists of plain knitted courses 13, 14, 15 situated between courses 16, 17, 18 provided with crossing loop legs. The courses 16, 17, 18, may be also described as consisting of uniformly twisted or turned loops.

Therefore, the knitting method in accordance with the present invention consists in forming a plain knitted course, such as the course 13, and suspending the loops thereof upon twisted loops of the following course, such as the course 17, whereupon the twisted loops are suspended upon straight loops of the next course, and so forth.

A method of knitting the fabric 10 is illustrated diagrammatically in Figure 3, which shows the formation of the fabric 10 by hand knitting, namely, by the use of the usual knitting needles 11 and 12.

Figure 3 shows twisted loops 47, 48 and 49 of a course 50. Loops 51, 52 and 53 of the following plain knitted course 54 carry the loops 47, 48 and 49, respectively, so that transverse rows of knitted stitches are formed. The twisting of a loop 55 carrying the loop 53 and situated on the needle 11, is accomplished by pulling the leg 56 of the loop 55 which is situated behind the needle 11 (looking in the direction of Figure 3) by the needle 12 to the right of and behind the other leg 57 which normally would have been engaged by the needle 12. The needle 12, after being moved behind the needle 11 and after engaging the rear leg 56 of a loop 55, receives a twisted loop, and by repeating this procedure a course of twisted loops, such as a course 16, 17 or 18 of Figure 1, is formed upon the needle 12.

While Figure 3 illustrates the formation of a fabric 10 by manual means, the same twisting of the loops may be conveniently accomplished on knitting machines of the type now in use for the manufacture of hosiery.

Figure 2 shows the manner in which the knitted fabric 10 prevents the extension of a run. It is assumed that the rupture has taken place at the point 58 (Fig. 1), namely, in the leg 28 of a loop 30 situated in the course 14 and the wale 19. The pull on the fabric will then cause a contraction of the loop 24 situated directly below the loop 30. The legs 27 and 26 of the loop 24 will spread outwardly while the bight 25 of the loop 24 will be drawn substantially tightly over the legs 28 and 29 of the broken loop 30 and will bring these legs closer to the bight 31 of the loop 32 in the course 13. Thus the bight 25, by holding

tightly the legs 28 and 29 and by pressing them against the bight 31, will result in the aggregation of thread at one place in the fabric, which serves substantially as a knot and which effectively prevents the spreading of the run.

The fabric 60 shown in Figure 4 consists of courses 61, 62, etc., each of which is substantially similar to the other and consists of twisted loops 63. Plain knit courses are entirely eliminated in this fabric, so that a bight of each loop of the knitted fabric is situated next to a pair of intersecting legs of a loop in the subsequent course. It is apparent that, in the case of any rupture of a loop of this fabric, the bight holding the ruptured loop will be also drawn together in the manner shown in Figure 2, thereby preventing the spreading of the run.

It is apparent that the specific illustrations shown above have been given by way of illustration, and not by way of limitation, and that the articles and the methods above described are subject to wide variation and modification without departing from the scope or intent of the invention. All of such variations and modifications are to be included within the scope of the present invention.

What is claimed is:

1. A knitted fabric comprising courses of loops each of which includes a bight and two adjoining legs, the legs of the loops constituting each alternate course only of the fabric crossing each other close to the bight of a loop in a preceding course to cause the twisting of said loops.

2. A knitted fabric comprising plain knit courses and courses consisting of twisted loops and alternating with said plain knit courses, the two legs of each of the twisted loops crossing each other close to the bight of a loop situated in the same wale and the preceding plain knit course.

3. A method of hand knitting by the use of two pointed needles on one of which the stitches are formed successively, said method comprising pulling a leg of the last loop on the first-mentioned needle of each alternate course only across and behind the other leg of that loop to form a twisted loop on the second-mentioned needle.

4. The method of knitting a fabric which comprises forming rows of knitted stitches and twisting the loops of each alternate transverse row only of said stitches prior to the formation of a succeeding row.

5. A method of hand knitting by the use of two pointed needles on one of which the stitches are formed successively, said method comprising forming transverse rows of stitches by plain knitting and forming alternating rows of twisted loops by pulling a leg of the last loop on the first-mentioned needle across and behind the other leg of that loop to form a twisted loop on the second-mentioned needle.

ESTER HUGHES.
